E. Arthur

Attest:

UNITED STATES PATENT OFFICE.

JOHN B. HEVERLING, OF ST. LOUIS, MISSOURI.

CABLE-RAILWAY GRIP.

SPECIFICATION forming part of Letters Patent No. 374,963, dated December 20, 1887.

Application filed March 28, 1887. Serial No. 232,736. (No model.)

To all whom it may concern:

Be it known that I, JOHN B. HEVERLING, of the city of St. Louis, in the State of Missouri, have invented certain new and useful 5 Improvements in Cable - Railway Grips, of which the following is a full, clear, and exact description, reference being had to the accompanying drawings, forming part of this specification, and in which—

10 Figure I is a side elevation of my grip. Fig. II is a detail side view showing the lower part of the grip with the plates removed. Fig. III is a detail end view of that portion of the grip below the conduit-rail, showing the cable resting on one of the anti-friction rollers. Fig. IV is an enlarged detail end view of one 15 of the links. Fig. V is an enlarged detail vertical section of the endless-chain friction-links, taken on line V V, Fig. VI. Fig. VI is an enlarged detail top view of the friction-links. Fig. VII is an enlarged detail horizontal section of the friction-links, taken on line VII VII, Fig. V. Fig. VIII is an enlarged top 20 view of the supporting-wheel of the grip and the fender. Fig. IX is an enlarged perspective view of the outside friction-link. Fig. X is an enlarged perspective view of the inside 25 friction-link.

My invention relates to a grip for cable 30 railways; and it consists in features of novelty, hereinafter fully described, and pointed out in the claims.

Referring to the drawings forming part of this specification—

35 1 represents the two uprights of the grip-frame, which support the several parts of the grip mechanism. They are surmounted by the double rack-arch 2.

40 The double grip-beam 3 consists of two horizontal parallel bars or plates that are secured by their ends to each side of the uprights of the frame, leaving a narrow space between them the thickness of the uprights for the working of the depressing-plate that actuates the grip. Portions of the grip-beam extend 45 beyond the uprights and have journal-bearings 4, in which work the axles 5 of the wheels 6, which travel on the slot-rails 7 and which support the grip, and thus relieve the grip-car of 50 the weight and jar resulting from the action of the grip, and, also, extending, as they do,

beyond the grip frame, they steady and brace the grip.

8 is a fender secured to the extensions 9 of the grip-beam. The fenders protect the wheels 55 and clear away any obstructions that may be lying on the slot-rails.

10 are cross-bars secured to the sides of the uprights 1 by rivets or otherwise, and near the center of said cross-bars are the pivot-bearings 60 11 of the operating-lever 12. The lever works between the two guides 2, on which are ratchet-racks 13 and 14, of which the teeth stand in opposite directions.

15 and 16 are pawls engaging, respectively, 65 the racks 13 and 14. These pawls are secured to the lever and work on the pivot-pin 17. The pawl 15 engages the rack 13 and holds the parts in braking position, while the pawl 16 engages the rack 14 and holds the parts in 70 gripping position. The former position is shown in Fig. I. The pawls are connected to rods 18 and 19, by which they may be lifted in the usual manner.

75 The part of the hand-lever below the fulcrum 11 is marked 20, and is connected by a pintle-pin, 21, to the upper end of an extension-link, 23. The two heads 22 of the link are connected by the screw-threaded coupling-bolt 24, that is made with right and left hand 80 screw-threads, which screw into the heads 22.

25 are jam-nuts which turn on the bolt and have bearing on the heads to hold the bolt to its adjustment. The lower head 22 of the link is connected by a pintle, 27, to the movable plate or head 26, carrying the upper grip-jaw and the friction-brake. On the lower end of the plate 26 there are placed anti-friction rollers 28, which work on pivot-pins 29.

30 is an endless chain which works over 90 the friction-rollers 28. The friction-chain is constructed of links 31 and 32. The construction of the links is shown in Figs. IX and X, the former showing one of the side links and the latter one of the middle links. Between 95 the friction-rollers 28 is a fixed block, 33, around which the chain runs when the grip is not loose. The friction of the links on the block prevents the movement of the chain when the cable is gripped fast.

100 The link 31 has rounded ends 34 and has filling projections 35 on the inner side, which

fill the spaces between the rounded ends of the central links, 32, so that the straight part 36 of the chain is solid, (see Figs. II and VI,) and the chain has solid bearing-faces against 5 the block 33 on one side and the cable on the other side. The links 31 have round recesses 37 concentric with their rounded ends 34, to receive the rounded projections 41 of the central links, 32, said projections and recesses forming the articulation of the links. The links are locked together by pintle-pins 42, passing centrally through the articulation.

The outer bearing-surface of the chain 30 is grooved at 37 to fit the cable, while the inner face is flat to fit the faces of the anti-friction rollers and the bearing-surface of the block 33. The central links, 32, have projections 40 on both sides to fill the space between the rounded ends 34 of the links 31 for the same 20 purpose as the projections 35 of the links 31.

The arbors 29 of the anti-friction rollers 28 are supported in the side plates 38, whose ends 39 overlap the uprights. These side plates also give support to the blocks 33, which 25 are riveted or otherwise secured between them. The side plate 38, upon one side, (or both,) carries a brake-shoe, 43, which, when the upper grip-jaw is lifted to its highest extent, as seen in Figs. I and III, bears against the under side of the grip-slot rail and stops the car.

To the lower ends of the uprights 1 is attached the lower and fixed jaw, 44, having at each end rollers 45, on which the cable 46 constantly bears. These rollers turn on arbors 35 47, fixed in the side plates 48, which are themselves attached to the upright 1. This jaw has anti-friction rollers, endless chain, and

bearing-block similar to that described in connection with the moving jaw.

As hereinbefore said, when the parts are in 40 the position shown in Figs. I and III, the cable is not gripped and the brake 43 is applied to the slot-rail. To unbake the car, the pawl 15 is disengaged from rack 13 and the lever moved to the left. This causes the movable 45 jaw to descend, and a sufficient movement causes the cable to be gripped.

The grip may be retained by the pawl 16 engaging the rack 14. This position of the jaws is shown in Fig. II. 50

I claim as my invention—

1. The fender 8, in combination with a cable-grip supported on wheels running on the grip-slot rails.

2. The endless bearing-chains articulated on 55 rounded projections cast upon each alternate link, entering similar recesses in the other links, and held together by pintle-pins passing centrally through the articulations.

3. The bearing-chains composed of links 60 rounded at the ends concentrically with the axis of articulation, and filling projections occupying, when the chain is straight, the space between the rounded ends, substantially as set forth.

4. The bearing-chain grooved at the outer side to fit the cable, and having the spaces between the rounded ends of the links filled by projections of the intermediate links, substantially as set forth. 65

JOHN B. HEVERLING.

In presence of—

GEO. H. KNIGHT,
JOSEPH WAHLE.
